The ornamental design for two-sack type protector for an electronic device, as shown and described.

DESCRIPTION

FIG. 1 is a perspective view of two-sack type protector for an electronic device showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof; and,
 FIG. 8 is a sectional view taken along line A—A in FIG. 2.
